PILE WIRE FOR DOUP HEDDLE LOOMS

William H. Hall, Jr., Trenton, N. J., assignor, by
mesne assignments, to Thermoid Textile Com-
pany, Trenton, N. J., a corporation of New Jersey

Original application September 2, 1933, Serial
No. 688,019. Divided and this application Oc-
tober 25, 1934, Serial No. 749,979

7 Claims. (Cl. 139—47)

The present application is a division of the copending parent application Serial No. 688,019, filed September 2, 1933.

This invention relates to the weaving of pile fabrics, such as carpet, on a loom normally adapted for the weaving of plain non-pile fabrics, such as canvas or asbestos fabric of the character normally used in the making of brake linings and clutch facings, wherein the sheet or web of fabric after weaving on the loom is cut and folded to provide a required number of layers or plies in the finished frictionized material.

The loom is of an ordinary type of well known construction including the usual plurality of heddle frames for manipulating the warp threads in forming open sheds for the passage of the shuttle in carrying a weft thread through the open warp shed in the production of a common one-over-one or a twill weave; and normally is not equipped with any mechanism for forming a pile face on the fabric.

The present invention relates to equipment adapted to be incorporated in a loom of the type noted, whereby a plain pile faced fabric may be produced thereon, all as will be fully disclosed hereinafter, reference being had to the accompanying drawings, of which:

Fig. 1 is a longitudinal sectional elevation of sufficient of a loom of the type noted to illustrate the operation of the elements of the present invention as applied thereto;

Fig. 2 is a fragmentary view similar to Fig. 1, drawn to an enlarged scale, illustrating certain parts of the mechanism of Fig. 1;

Fig. 3 is a fragmentary perspective view of the support for the rear ends of the stationary pile wires;

Fig. 4 is a fragmentary perspective view of the support for the front ends of the stationary pile wires; and

Fig. 5 illustrates a detail of the invention.

As shown in the drawings, the loom comprises the usual transversely extending breast beam 1, a series of transversely extending heddle frames 2, 3, 4, 5 and 6, in the present instance, and a lay 7 provided with the usual reed or comb having a series of dents 8 formed by and between a series of laterally spaced blades 9, 9.

In the present instance the warp in the loom comprises a series of stuffer warp threads *s*, a series of chain warps *c*, a second series of chain warps *c'* and a series of pile warps *p*, all of which extend longitudinally of the loom through the heddle frames and dents of the reed.

Also extending longitudinally of the loom, through the heddle frames and lay reed, is a series of pile wires 10, 10, the front ends of which terminate adjacent the breast beam 1 and are each provided with a head 11, clearly shown in Figs. 1 and 2.

Each head 11 is provided with a forwardly extending lug or projection 12, which is seated in a horizontal groove 13 formed in the rear face of a bridge beam 14; and a shoulder 15 abutting the rear face of the bridge beam 14, to prevent forward longitudinal movement of the pile wires 10, 10.

Each of the heads 11 is provided with a rearwardly extending lug or projection 16 overhanging the forward end of the associated pile wire 10. The projection 16, in each instance, is provided with a depending lip 17 (see Fig. 5), the underside of which, and the corresponding upper side of the adjacent portion of each pile wire 10 are grooved as indicated at 18 and 19 respectively, to receive a thin removable blade 20. Each blade 20 is provided with a cutting edge 21, which is disposed at an acute angle to the upper edge of the pile wire. Each blade 20 is shouldered, as indicated at 22, to abut the rear edge of the projection 16, to prevent forward longitudinal movement of the blade relative to the pile wire.

The rear end of each of the pile wires 10 is provided with a slot or eye 23 (see Fig. 3), which is adapted to receive a readily removable bar 24 on which the series of pile wires is threaded. The bar is supported by a rear beam 25 which extends transversely of the loom and is permanently fixed, at its opposite ends, to the side frames 26 of the loom, as indicated in Fig. 3. A staple or hook 27 is provided adjacent each end of the bar 24 and rigidly secured in the rear beam 25, to receive the bar 24 and secure the same in fixed relation to the rear beam 25, each end of the bar 24 being provided with an opening 28 adapted to receive a cotter pin 29, outside the staple 27, whereby longitudinal movement of the bar 24 is prevented.

The pile wires 10, while being stationary, insofar as longitudinal movement in the loom is concerned, are permitted a slight relative lateral movement in the slot 13 at their forward ends and on the bar 24 at their rear ends, to prevent binding of the pile wires against the blades 9 of the reed, as the lay 7 reciprocates intermediate the breast beam 1 and the first of the heddle frames 2.

The front ends of the pile wires 10 may be

readily removed from the supporting slot 13 of the bridge 14 by the removal of a bar 30, the lower surface of which forms the upper surface of the slot 13, which is secured to the bridge 5 beam 14 by means of bolts 31, as clearly shown in Fig. 2.

The bridge beam 14 is spaced above the upper face of the breast beam 1, to provide a fabric passage or slot 32, by means of blocks 33 disposed at the opposite ends of the bridge beam 14, between the said bridge beam and the said breast beam, the bridge beam 14, the blocks 33, and the breast beam 1 being secured together as a unit by means of screws or bolts 34.

15 As shown in Fig. 1, the stuffer warps *s* are under the control of the heddle frame 6 while the chain warps *c* and *c*¹ are controlled by the heddle frames 4 and 5 respectively. The pile warps *p* are each under control of a doup heddle 35.

20 The doup heddles are operated in the manner described in the above noted parent application, to carry the pile warps *p* down first on one side of the pile wires 10, then on the opposite side.

The pile wires and the mounting therefor, 25 which form the subject matter of the present application, are so constructed and supported that in event of it being necessary for the weaver to tie in broken warp ends the pile wires 10 may be separated in the same manner as the warp 30 threads, i. e. pushed aside by the weaver's hands in getting in at the broken thread in the shed underlying the pile wires, due to the flexibility of the wires and upon withdrawal of the weaver's hands the wires will reassume their normal relative positions immediately or upon the next movement of the lay wherein the blades 9 will comb the wires into place. This is made possible by the fore and aft mountings of the pile wires 35 by which lateral relative movement of the wires 40 is permitted.

I claim:

1. In a loom, comprising a breast beam, the combination therewith of a series of pile wires extending substantially at right angles to the 45 breast beam in a substantially horizontal plane, a bridge beam spaced above and substantially paralleling the breast beam and provided with a horizontally extending groove, a head on and formed integral with each pile wire and of a 50 width not exceeding the width of the wire, said head having a projection extending into said groove for holding each pile wire against vertical movement and providing for lateral relative movement between the pile wires, a shoulder on 55 each head engaging the bridge beam to prevent longitudinal movement of the pile wires, a projection on the head and overhanging the pile wire, a removable blade inserted in a slot formed in the upper edge of the pile wire adjacent the 60 head and into a slot formed in the rear edge of the overhanging projection of said head and having a cutting edge projecting at an angle from the upper edge of the pile wire to the overhanging projection on the head, and a 65 shoulder on the blade engaging the base of the slot in said rear edge of said projection on the head to prevent longitudinal movement of the blade relative to the wire.

2. In a loom, comprising a breast beam, the 70 combination therewith of a series of pile wires extending substantially at right angles to the breast beam in a substantially horizontal plane, a bridge beam spaced above and inwardly from the front edge of the breast beam and substantially paralleling the breast beam and provided

with a horizontally extending groove in its rear face for the reception of the ends of the pile wires and loosely holding said ends of said wires against forward longitudinal and vertical movement and providing for lateral relative movement therebetween in said groove, and a removable bar secured to the back face of the bridge beam and constituting the upper side of the wire-supporting groove to facilitate removal of the pile wires 5 from the bridge beam.

3. In a loom, comprising a breast beam, the combination therewith of a series of pile wires extending substantially at right angles to the breast beam in a substantially horizontal plane, a bridge beam spaced above and substantially 15 paralleling the breast beam and provided with a horizontally extending groove for the reception of the ends of the pile wires for holding said ends of said wires against longitudinal and vertical movement and providing for lateral relative movement therebetween in said groove, a rear beam supporting the rear ends of the pile wires, and a readily removable bar extending through formed eyes in the said rear ends of the pile wires to secure the pile wires to the rear 20 beam.

4. In a loom comprising a breast beam, a warp-controlling harness, a back beam substantially parallel to the breast beam and disposed behind said harness and a lay having a reed comb oscillating intermediate the breast beam and the harness, said loom having a woven fabric passing over the breast beam and a divergent open warp shed extending rearwardly from the fabric through said reed comb and the harness, a bridge beam spaced above the breast beam and fabric, pile wires extending rearwardly from the bridge beam through the reed comb and the harness with one portion thereof substantially parallel to the fabric and supported by the bridge beam, a second portion thereof inclined to the first said portion and disposed above and substantially parallel to the upper portion of said open warp shed, and a third portion substantially parallel to the first said portion and lying to the rear of 30 said lay and extending through the harness and anchored at their back ends to said back beam. 35

5. In a loom comprising a breast beam, a warp-controlling harness, a back beam substantially parallel to the breast beam and disposed behind said harness and a lay having a reed comb oscillating intermediate the breast beam and the harness, said loom having a woven fabric passing over the breast beam and a divergent open warp shed extending rearwardly from the 50 fabric through said reed comb and the harness, a bridge beam spaced above the breast beam and fabric, pile wires extending rearwardly from the bridge beam through the reed comb and the harness with one portion thereof substantially parallel to the fabric, a second portion thereof inclined to the first said portion and disposed above and substantially parallel to the upper portion of said open warp shed, and a third portion substantially parallel to the first said portion and 55 lying to the rear of said lay and extending through the harness and anchored at their back ends to said back beam, said bridge beam having a rear groove in which the front ends of said pile wires are slidably mounted for relative lateral movement.

6. In a loom comprising a breast beam, a warp-controlling harness, a back beam substantially parallel to the breast beam and disposed behind said harness and a lay having a reed comb os- 75

cillating intermediate the breast beam and the harness, said loom having a woven fabric passing over the breast beam and a divergent open warp shed extending rearwardly from the fabric 5 through said reed comb and the harness, a bridge beam spaced above the breast beam and fabric, pile wires extending rearwardly from the bridge beam through the reed comb and the harness with one portion thereof substantially parallel 10 to the fabric, a second portion thereof inclined to the first said portion and disposed above and substantially parallel to the upper portion of said open warp shed, a third portion substantially parallel to the first said portion and lying 15 to the rear of said lay and extending through the harness and anchored at its back end to said back beam, said bridge beam having a rear groove in which the front ends of said pile wires are slidably mounted for relative lateral movement, and a shoulder adjacent the front end of 20 each wire bearing against the rear face of the bridge beam and preventing forward longitudinal movement of said wires.

7. In a loom comprising a breast beam, a back

beam substantially parallel thereto and a lay having a reed comb oscillating intermediate said beams, said loom having a woven fabric passing over the breast beam and a divergent open warp shed extending rearwardly from the fabric 5 through said reed comb, a bridge beam spaced above the breast beam and fabric, pile wires extending rearwardly from the bridge beam through the reed comb with one portion thereof substantially parallel to the fabric, a second portion 10 thereof inclined to the first said portion and disposed above and substantially parallel to the upper portion of said open warp shed, and a third portion substantially parallel to the first said portion and lying to the rear of said lay 15 and anchored at its back end to said back beam, said anchorage comprising a bar parallel to, spaced from, and secured at its opposite ends to said back beam and having its central portion passing through eyes respectively formed in the 20 back ends of said pile wires allowing relative lateral movement of the wires on said bar.
